UNITED STATES PATENT OFFICE.

ARTHUR A. JOHNSON, OF NEW YORK, N. Y., ASSIGNOR, BY MESNE ASSIGNMENTS, TO
UNDERWOOD TYPEWRITER COMPANY, OF NEW YORK, N. Y., A CORPORATION OF
DELAWARE.

COLLATING DEVICE.

Application filed August 15, 1918. Serial No. 250,089.

To all whom it may concern:

Be it known that I, ARTHUR A. JOHNSON, a citizen of the United States, and a resident of the city of New York, county of the Bronx and State of New York, have invented an Improvement in Collating Devices, of which the following is a specification.

This invention relates to collating devices and more especially to such devices as are particularly adapted to be used in connection with typewriting machines, to handle the sheets used in bookkeeping and other systems where records can be profitably kept by means of carbon copies, and entries are made at greater or less intervals of time.

In continuous ledger posting each ledger sheet is usually kept with the monthly statement for the customer until the end of the current month, the ledger sheet and statement sheet being stored in a suitable receptacle and taken out to be written upon from time to time. At the end of the month all the statements are separated from their ledger sheets and the statements are sent to the customers.

The record of each transaction is usually typewritten upon the statement or top sheet and by means of a carbon sheet simultaneously recorded on the ledger sheet.

In the present invention I arrange to semi-permanently secure the ledger and statement sheets together so that the two sheets may be handled as one during the entire month.

The means employed for holding the two sheets together also facilitate the alignment and registration of these sheets with respect to the machine and with respect to any other sheet which may be simultaneously and conjunctively used with the statement and ledger sheets, such as, an invoice or record sheet. The specific means illustrated herein comprises a temporary or collating binder formed of paper or other suitable material and having a plurality of leaves to receive work-sheets therebetween. The work-sheets to receive the entries may be secured in place in the binder by gum or other suitable adhesive material. The binder is provided with a tab which co-operates with an abut-

men or gaging device for locating the sheets when placed in the machine. A modified form of this invention illustrates such a tab as provided with a perforation, by means of which it may be collated or gaged upon any

one of several pins or studs carried by the machine.

Other features and advantages will hereinafter appear.

In the accompanying drawings,

Figure 1 is a perspective view showing the sheets in collated position.

Figure 2 is a side elevation of the same.

Figure 3 is a detail showing the binder, part of one leaf being broken away to show the adhesive material.

Figure 4 is a sectional plan view of Figure 3.

Figure 5 is a front elevation showing a modified form.

Figure 6 is a front detail of the form of device of Figure 5.

The typewriter platen 10 is rotatably mounted in a carriage frame (not shown) to receive the usual intermittent line space movement from a pawl 11, which cooperates with a ratchet wheel 12, secured to the platen axle 13. In addition the platen may be moved in line space or reverse direction by means of the usual knob or finger piece 14.

The work sheets are fed around with the platen 10, by front and rear pressure rolls 15, which may be released by suitable means, such as, for instance, the means found in the Underwood typewriter. The work sheets are further guided around the platen 10 by means of an apron 16.

In printing, types 17 swing upwardly and rearwardly so as to strike against the work sheet carried by the platen. A pair of scales 18 indicate the writing line of the machine. Ordinarily these scales are used to align the work sheets with respect to the "line of writing" of the machine.

As has heretofore been said, the present disclosure, for simplicity, shows only one of the many possible forms of the invention. In this form, a statement sheet 19, being the top sheet, receives the direct inked impressions from the types 17, and the ledger sheet 20, lying beneath the statement sheet 19, receives the imprint from a carbon sheet 21. In this form of bookkeeping it is usual at the beginning, or just previous to the beginning, of each month to place with each ledger sheet 19, a fresh statement sheet 20 which is to receive the typing of the transactions, at intervals, during the ensuing month. The statement sheet, according to the present in-

vention, is temporarily secured to the ledger sheet, after being properly aligned so that the first line to be written upon the statement sheet coincides with the line following 5 the last line written upon the ledger sheet.

The means for forming this cooperative union between the ledger sheet and the statement sheet as illustrated in the present disclosure, comprises a binder 22 of paper or 10 other suitable material. This binder 22 may be formed of one piece 23 folded upon itself to form leaves 24, and 25, for the reception 15 of the work-sheets. The binder may be provided with a center leaf 26, of suitable material, thus forming a binder of three leaves 24, 25, and 26, and two pockets 27, and 28. The inner surface of the leaves 24, and 25, and both surfaces of the central leaf 26, may be provided with gum or other suitable adhesive material so that when the 20 work-sheets 19 and 20 are placed in the binder after the leaves of the same have been moistened, they are thereby confined and securely held in place with respect to one another, and with respect to the binder 22. The piece 23 and the leaf 26 are secured together, from the fold or bend 30 in the piece 25 inwardly for some distance, so as to provide a comparatively stiff tab 31 extending 30 outwardly from the bottom of the pocket formed by the leaves 25 and 26. The binder may be manufactured and marketed in this form.

When it is desired to prepare work-sheets 35 for bookkeeping, the gummed surfaces of the leaves 24, 25 and 26 are moistened and the work sheets 19 and 20 are placed in the pockets so that their side edges engage with the bottom of the pockets, formed by the 40 line of junction of the leaves 24, 25 and 26, thus aligning the sheets with respect to one another. After this is done the leaves 24 and 25 are pressed together and dried and all the sheets are thus secured to one another. 45 When entries are to be made, the statement sheet and the ledger sheet are placed in the machine and passed around the platen, while the feed rolls 15 are disengaged therefrom.

To facilitate the accurate alignment and 50 registration of the sheets with respect to the printing line, a gage plate having a turned-up aligning edge 32 is provided, the aligning edge being placed so as to be in the path of the tab 31 of the binder 22, with the result 55 that when the sheets are brought up in front of the platen and pressed upon the gage plate, the tab 31 engages the gage 32 and temporarily holds the sheets in this position. This arrests the sheets so that the 60 lines upon the statement and ledger sheets, which are usually printed as indicated in the drawings, correspond with the writing lines of the typewriting machine.

The sheets are laterally guided by and 65 gaged against a right-hand gage 33 and a

left-hand gage 34. The left-hand gage 34 is preferably made integral with the edge of the plate which comprises the gage 32, said plate having its edge turned up to form a right-angled gage. After the sheets are 70 so gaged and aligned the feed rolls 15 are returned to the platen and the platen is rolled rearwardly or forwardly as the case may be, to bring the proper line to the printing line, which is indicated by the two scales 75 18.

During the usual typewriting operation, the tab 31 will not remain engaged with the abutment 32 because the upper portions of the work-sheets tend to spring upwardly 80 above the abutment unless the tab is applied low on the ledger sheet. In this latter case the operator may simply lift the sheets or tab clear of the abutment when the tab engages with it.

It will be noted, that the binder 22 because of its flexibility and size will freely pass around the platen in the operation above described. This will also be the case if the binder 22 is made of metal, and the proper clearance between the platen and feed-rolls is provided.

Figures 5 and 6 illustrate a modification of my invention, which will now be described, in which a main body member or 95 binder 35 is similar to the binder 22 of Figures 1, 2, 3 and 4, in that it has leaves similar to the leaves 24 and 25 and 26 and is folded upon itself in the same manner. It is also provided with adhesive material for 100 holding work-sheets as described in connection with the other figures. In fact, Figure 4 serves as a plan view of this member 35. The extending portion or tab 36 of this member, while very similar to the tab 31, is 105 provided with a perforation 37, by means of which the sheets are brought into registration with the writing lines of the machine. This perforation 37 is adapted to fit over any of a plurality of aligning studs 38 110 mounted upon a plate 39 suitably secured to the machine, the sheets being passed around the platen in the usual way, so that the tab 36 may be fitted over one of the studs 38 to bring the sheets into registration with the 115 writing lines of the machine. This form of device under some circumstances is advantageous because of the increased speed at which the work may be handled.

The work sheets may be provided with 120 tabs or aligning members 31 or 35 at either or both sides, if so desired, as illustrated in connection with the modified form shown in Figure 5. This also under some circumstances may be advantageous.

The work sheets are provided with a row of small perforations 40 so that the side margins of the sheets to which the leaves of the collating member are attached may be removed when it is desired. Of course this 130

margin of the statement sheet would be severed from the body of the sheet before the bill is sent to the customer.

Variations may be resorted to within the scope of the invention, and portions of the improvements may be used without others.

Having now described my invention I claim:

1. A collating binder for work-sheets comprising a plurality of leaves certain of said leaves confined between others thereof, all of said leaves secured together at one side, holding means associated with each of said leaves to hold in collated position work-sheets inserted between the free portions of said leaves, and a tab on said binder and projecting outwardly from the side edges of said work-sheets to facilitate the handling and positioning of the latter while held by the collating binder, said tab being perforated so as to fit over an aligning pin and to be positioned and held by the latter.

2. A collating binder for work-sheets including a binder-sheet folded upon itself to form two leaves, said binder also including a leaf inserted between the leaves of said binder-sheet and secured thereto, and holding means for each of said leaves to hold in collated position work-sheets inserted between said leaves.

3. A collating binder for work-sheets including a binder-sheet folded upon itself to form two leaves, said binder also including a leaf inserted between the leaves of said binder-sheet and secured thereto, and holding means to hold in collated position work-sheets inserted between said leaves, said holding means comprising adhesive material on a face of each of said leaves for holding the work-sheets in position thereon.

4. An assemblage for use in manifolding, comprising a collating binder having a plurality of leaves secured together at one side and having adhesive material on certain faces thereof, and a plurality of work-sheets having detachable margins to be inserted between said leaves and attached thereto by said adhesive material when the work-sheets

are assembled in proper relation to each other, the detachable margins of the work-sheets permitting the latter to be removed from the assemblage when the necessity for maintaining them in collated condition no longer exists.

5. An assemblage for use in manifolding, in a typewriting machine, comprising a plurality of work-sheets properly collated with reference to each other and binders for holding said work-sheets at opposite edges to prevent relative displacement thereof, each of said binders comprising a plurality of leaves between which the edges of the work-sheets may be inserted and a tab projecting from the adjacent edges of said work-sheets, the tabs on the binders being in alignment transversely of the work-sheets and serving as means to align the assemblage in the machine.

6. An assemblage for use in manifolding, in a typewriting machine, comprising a plurality of work-sheets properly collated with reference to each other and binders for holding said work-sheets at opposite edges to prevent relative displacement thereof, each of said binders comprising a plurality of leaves between which the edges of the work-sheets may be inserted and a tab projecting from the adjacent edges of said work-sheets, and each of said tabs having a perforation so that the tabs may be placed over two transversely aligned pins in the machine to properly align the assemblage in the machine.

7. A binder for holding work-sheets in collated position, comprising a plurality of attached leaves between two of which a work-sheet may be adjusted and held, and then a second work-sheet inserted in another opening between two leaves, adjusted in collated relation with reference to the first work-sheet, and held in such adjusted position.

In testimony whereof, I have signed my name to this specification.

ARTHUR A. JOHNSON.
